(57) **CLAIM**

The ornamental design for a smock, as shown and described.

DESCRIPTION

FIG. 1 is an isometric view of a smock showing my new design;

FIG. 2 is a front elevational view thereof;

FIG. 3 is a top view thereof; the bottom being a mirror image thereof;

FIG. 4 is a side elevational view thereof: the opposite side being a mirror image thereof;

FIG. 5 is a rear elevational view thereof;

FIG. 6 is a front elevational view thereof with slits and pockets being shown partially opened; and,

FIG. 7 is an enlarged scale fragmentary sectional view thereof taken substantially along the plane 7-7 of FIG. 6 and through a pocket.
